DESIGN FOR AN AIR CIRCULATOR

Herman C. Hueglin, Chicago, Ill., assignor to
Airmaster Corporation, Chicago, Ill., a corpora-
tion of Illinois

Application January 20, 1936, Serial No. 60,667

Term of patent 7 years

To all whom it may concern:

Be it known that I, Herman C. Hueglin, a citizen of the United States, residing at Chicago, in the county of Cook and State of Illinois, have invented a new, original, and ornamental Design for an Air Circulator, of which the following is a specification, reference being had to the accompanying drawing, forming a part thereof.

In the drawing, the single figure is a perspec-

tive view of an air circulator, showing my new design.

I claim:

The ornamental design for an air circulator as shown.

In witness whereof, I hereunto subscribe my name, this 16 day of January, 1936.

HERMAN C. HUEGLIN.
